UNITED STATES PATENT OFFICE.

WILLIAM E. WOODARD, OF LIMA, OHIO.

EXHAUST PASSAGE AND PIPE FOR LOCOMOTIVE-CYLINDERS.

1,325,068.

Specification of Letters Patent.

Patented Dec. 16, 1919.

Application filed March 1, 1918. Serial No. 219,776.

To all whom it may concern:

Be it known that I, WILLIAM E. WOODARD, a citizen of the United States, residing at Lima, in the county of Allen and 5 State of Ohio, have invented certain new and useful Improvements in Exhaust Passages and Pipe for Locomotive-Cylinders, of which the following is a specification.

This invention relates to an improvement 10 in the exhaust passages and pipe for locomotive cylinders, and is particularly useful in association with locomotives of the articulated type such, for example, as Mallet engines.

15 It has for one of its primary objects the provision of an arrangement whereby back pressure in the cylinders is greatly reduced and whereby what is termed "blowing over" is prevented. My invention also contemplates 20 the disposition of the exhaust passages and exhaust pipe in such manner that the exhaust steam has the shortest possible distance to travel in passing from the cylinders to the exhaust pipe in the smoke box.

25 The foregoing, together with such other objects as may hereinafter appear, I attain by means of a construction which I have illustrated in preferred form in the accompanying drawings, wherein—

30 Figure 1 is a side elevation and partial section through the front end of a locomotive of the Mallet type, equipped with my improvements; Fig. 2 is a partial plan view and section of my improved form of exhaust passages and pipe; and Fig. 3 is a front end elevation of Fig. 2.

35 My invention will be best understood from a brief description of the prior art, particularly that relating to the exhaust passages for articulated locomotives. In this class of locomotive, because of the use of articulated units, a flexible pipe connection to conduct the steam exhausted from the cylinders to the exhaust pipe located in the 40 boiler smoke box, is required. Exhaust passages and pipes for this purpose are not new but the exhaust passages and the connections to the exhaust pipe have been so arranged that the exhaust steam has to travel

45 through crooked passages, in some places restricted, as a result of which the undue resistance to the flow of the steam developed a high back pressure on the exhaust side of the pistons. In the Mallet type of locomotives this high back pressure is particularly 50 objectionable because it acts on the low pres-

sure pistons, whose areas are large, often exceeding three feet in diameter. By reason of the back pressure the total engine work is frequently reduced by a very large 55 figure.

In addition, in the exhaust passages and pipe arrangements ordinarily employed, a "blow-over" from the exhaust of one cylinder takes place to the other cylinder, this 60 occurring by reason of the fact that where the exhaust passages from the two cylinders meet, the stream of exhaust steam from one side is not properly directed or controlled, with the result that the back pressure 65 on the opposite side is raised, thereby reducing the engine work. This effect is often noted in steam engine indicator cards from low pressure cylinders of Mallet locomotives which cards, particularly at low 70 speeds, show a decided increase in back pressure at the time the opposite cylinder releases its exhaust.

In the accompanying drawings I have shown my invention as applied to cylinders 80 of the piston valve type in connection with which my improvements have great advantages. In Fig. 2 one of such cylinders A is shown in cross-section with the valve removed, and from inspection of this figure 85 it will be noted that the exhaust passages 7, which are formed in the cylinder castings, are led from each end of the steam chest cavity to a central opening or passage 8 located approximately on the same horizontal 90 level as the steam chest centers (see Fig. 2). It will be noted that by this arrangement full openings and easy curves are provided, offering a minimum resistance to the flow of the steam; and in addition this arrangement provides the shortest possible 95 length of passage. Short pipes 9 connect the exhaust passages 8 in each cylinder with a Y-shaped casting 10 in which the exhaust passages from the two cylinders meet, and 100 which forms a socket 11 to receive the end of the exhaust pipe 12 leading to the smoke box. The pipes 9 are provided with the ball joints 9a at the ends as shown to insure a steam-tight compensating connection. 105

The details of the exhaust pipe 12 and the specific construction of the ball and slip joints (see Fig. 1) are not new and are of conventional design, but it is to be noted that the arrangement of the exhaust passages, 110 pipes 9, and Y casting 10, is such that the openings or passage-ways in the Y casting

open directly into the end of the pipe 12, whereby the elbow which is found at such point in the conventional forms of this type of apparatus is eliminated. This elbow has 5 been found to present marked trouble in connection with blow-overs from one cylinder to the other.

It will be noted that the disposition of the parts is such that the path from the steam 10 chest to the pipe 12 is as direct as may be had, the curves are full and easy, and the exhaust steam is delivered into the pipe 12 so as to decrease the liability of blow-over. I also provide a restriction in the passages in 15 the Y casting at the points marked *a* in Fig. 2 for the purpose of assisting in preventing or reducing the blow-over, the operation of such restriction being to increase the velocity of the exhaust steam and as it were 20 inject the steam from the converging passages into the common passage. By this operation the steam as it is exhausted from one passage has an entraining effect on the other passage and tends to reduce the pressure in 25 such passage.

I claim:

1. In a locomotive the combination of a 30 pair of steam chests, a nozzle stand located on one side of the transverse vertical center line of the chests, a horizontally disposed Y-pipe intermediate the chests, laterally opening and inwardly extending exhaust passages communicating with the branches of the Y-pipe, and an exhaust pipe connecting 35 the Y-pipe to the nozzle stand.

2. In a locomotive the combination of a pair of steam chests, a nozzle stand located on one side of the transverse vertical center line of the chests, a substantially horizontally disposed Y-pipe intermediate the 40 chests, exhaust passages opening laterally and centrally of the steam chests and leading inwardly therefrom and communicating with the branches of the Y-pipe, and an exhaust pipe connecting the Y-pipe to the nozzle stand.

3. In a locomotive the combination of a pair of steam chests, an exhaust stand located on one side of the transverse vertical center line of the chests, a horizontally disposed Y-pipe intermediate the chests, laterally opening and inwardly extending exhaust 50 passages communicating with the branches of the Y-pipe, and an exhaust pipe connecting the Y-pipe to the exhaust stand, 55 said branches of the Y-pipe being restricted.

4. In a locomotive the combination of a pair of steam chests, a nozzle stand located on one side of the transverse vertical center line of the chests, a horizontally disposed 60 Y-pipe intermediate the chests, laterally opening and inwardly extending exhaust passages communicating with the branches of the Y-pipe, and an exhaust pipe connecting the Y-pipe to the nozzle stand, said Y-pipe having means for increasing the velocity of the steam at the point of juncture. 65

In testimony whereof, I have hereunto signed my name.

WILLIAM E. WOODARD.
